UNITED STATES PATENT OFFICE.

GEORGE HENRY CHALLENGER, OF WESTMINSTER, LONDON, AND HAROLD ARTHUR SAVAGE, OF BEXLEY HEATH, ENGLAND, ASSIGNEES TO VICKERS LIMITED, OF WESTMINSTER, ENGLAND.

AUTOMATIC GUN.

1,298,887.

Specification of Letters Patent. Patented Apr. 1, 1919.

Application filed July 6, 1917. Serial No. 179,090.

To all whom it may concern:

Be it known that we, GEORGE HENRY CHALLENGER and HAROLD ARTHUR SAVAGE, both subjects of the King of Great Britain, residing, respectively, at Vickers House, Broadway, Westminster, in the county of London, England, and Bexley Heath Works, Gravel Hill, Bexley Heath, in the county of Kent, England, have invented certain new and useful Improvements in or Relating to Automatic Guns, of which the following is a specification.

This invention relates to automatic guns of the Lewis, Hotchkiss or similar type in which when the trigger or sear is actuated to fire the gun, the bolt has to move forward to insert a new cartridge into the barrel before firing occurs, as distinct from the type of gun, such as the Vickers automatic gun, in which, when the gun is ready for firing, the bolt is in its forward position with the cartridge in the barrel, the actuation of the trigger or sear then merely releasing the striker. The chief object of the present invention is to convert a gun of the first mentioned type into one that will operate like one of the second mentioned type; by so doing the consequent reduction in the lapse of time from the instant of actuating the trigger or sear to the instant of impact of the striker with the head of the cartridge, renders the converted gun particularly applicable for firing between the propeller blades of aircraft and for the firing to be controlled by the aircraft engine.

According to the present invention, we provide means whereby the striker spring does not become energized during the rearward movement of the aforesaid striking post or other member, but becomes energized during the forward movement of this member. In this manner we are able to reduce the size of the spring and are able to place the spring within the mechanism casing of the gun, thereby avoiding the necessity of arranging the spring within a casing attached to the butt tang or butt fitting. Furthermore, as the spring is not energized during the rearward movement of the striking post, no undue impediment is offered to the proper rearward movement of the breech mechanism.

In order that the said invention may be clearly understood and readily carried into effect, we will describe the same more fully

with reference to the accompanying drawings, in which:

Figure 1 is a sectional side elevation showing more or less diagrammatically a constructional form of our improvements, the bolt being shown in its forward position and the striker in its fired position.

Fig. 2 is a view similar to Fig. 1 but showing the bolt in its rearmost position.

The firing mechanism is shown in conjunction with the breech mechanism of a Lewis gun, this mechanism comprising a bolt A, a feed operating stud A' connected to the bolt, a rack B and a striking post B' forming part of the rack. C is the striker loosely mounted in the striking post B' and D is the striker spring. This spring is of the helical compression type disposed in a casing D' attached by screw threads or otherwise to the feed operating stud A'. This spring bears at one end against a collar C' on the striker and at the other end against a plunger E arranged in contact with an arm E' or lever which is pivoted at e to the spring casing D' and is actuated, during the forward movement of the striking post B', to move the plunger E forward by reason of a cam e' on this arm bearing against the rear end of the plunger and thereby compressing the striker spring D. In order to effect the actuation of the arm E', the rear portion of the rack B has attached thereto a rearwardly extending bar B² having an inclined or cam shaped operating surface b² which engages with the arm, during the forward movement of the rack B and its striking post B', to rock the arm in the direction of the arrow in Fig. 1 for compressing the spring in such a manner that when the parts are in the position ready to fire (with the spring cocked) the compression of the said spring cannot pull the rack B' backward from its home position. This rocking movement of the arm E' to effect the compression of the striker spring, occurs during the final portion of the forward movement of the rack and its striking post relatively to the bolt and after the latter has been locked by its rotary movement. The striker spring thus also serves as a buffer to bring the rack and the striking post gently to rest. During the time that the arm is compressing the striker spring, the striker is prevented from moving forward by a shoulder or collar d on a rearward ex-

tension of the striker coming against a trigger or sear d' and the striker is thereby cocked. It will be observed that the striker spring is thus compressed from both ends, 5 at its rear end by the aforesaid arm and at its forward end by the aforesaid collar C' on the striker. During the rearward movement of the rack B and its striking post B', a stop b^2 on the rearwardly extending bar 10 b^2 comes against the arm and rocks it in the direction of the arrow in Fig. 2 and permits the plunger E to move rearward slightly under the influence of the striker spring D. In this way the energization of 15 the spring is relieved so that when during the final portion of the rearward movement of the rack and its striking post relatively to the bolt, the said post comes into contact with a shoulder on the striker, the latter can be 20 moved rearward slightly in order to withdraw the point of the striker within the front face of the bolt as shown in Fig. 2.

What we claim and desire to secure by Letters Patent of the United States is:—

- 25 1. In an automatic gun, the combination with the breech bolt, of a member for operating said bolt, a spring actuated striker loosely carried by said member and a device carried by the bolt and operated by said member for energizing the spring during the forward movement of said member.
- 30 2. In an automatic gun, the combination with the breech bolt, of a gas operated member for actuating said bolt, a spring actuated striker loosely carried by said member and a device carried by the bolt and operated by said member for energizing the spring during the forward movement of said member.
- 35 3. In an automatic gun, the combination with the breech bolt, of a member for imparting angular and axial movement to the bolt, a spring actuated striker loosely carried by said member and a device carried by the bolt and operated by said member for energizing the spring during the forward movement of said member.
- 40 4. In an automatic gun, the combination with the breech bolt, of a striking post for operating the bolt, a spring actuated striker loosely mounted in said post and means for energizing the spring during the forward movement of said post.
- 45 5. In an automatic gun, the combination

with the breech bolt, of a striking post for 65 operating the bolt, a spring actuated striker loosely mounted in said post, a casing attached to the breech bolt, said casing receiving the striker spring, a pivoted member controlling said spring and means for displacing said member during the forward movement of the post to energize the spring. 60

6. In an automatic gun, the combination with the breech bolt, of a striking post for 65 operating the bolt, a spring actuated striker loosely mounted in said post, a casing attached to the breech bolt, said casing receiving the striker spring, a pivoted member controlling said spring, means for displacing said member during the forward movement of the post to energize the spring, 70 and a sear which engages with the striker during the forward movement of the post to further energize the spring. 75

7. In an automatic gun, the combination with the breech bolt, of a striking post for 80 operating the bolt, a spring actuated striker loosely mounted in said post, a casing attached to the breech bolt, said casing receiving the striker spring, a pivoted member controlling said spring, means for displacing said member during the forward movement of the post to energize the spring, and means whereby, during the rearward movement of the striking post, the said member is displaced to relieve the energization of the spring so as to enable the striker to be moved rearward by the post to withdraw the point of the striker within the 90 front face of the bolt. 85

8. In an automatic gun, the combination with the breech bolt, of a striking post for 95 operating the bolt, a spring actuated striker loosely mounted in said post, a rearward extension on the striker for engaging with a trigger or sear, a casing attached to the bolt for receiving the striker spring, a plunger against which one end of the spring bears, an arm pivoted to the casing and provided with a cam surface bearing against the plunger, and a rearward extension on the said post, this extension serving to operate the pivoted arm. 100

In testimony whereof we affix our signatures. 105

GEORGE HENRY CHALLENGER.
HAROLD ARTHUR SAVAGE.
